UNITED STATES PATENT OFFICE.

JAMES H. POU, JR., OF RALEIGH, NORTH CAROLINA.

ERASER-PAD.

1,311,245.

Specification of Letters Patent. Patented July 29, 1919.

Application filed February 25, 1919. Serial No. 279,095.

To all whom it may concern:

Be it known that I, JAMES H. POU, Jr., a citizen of the United States, and a resident of Raleigh, in the county of Wake and State of North Carolina, have invented certain new and useful Improvements in Eraser-Pads, of which the following is a specification.

My invention relates to improvements in eraser pads, it being more particularly in the nature of an attachment to be used on a typewriter, and consists in the constructions, combinations and arrangements herein described and claimed.

15 The foremost object of my invention is to provide an eraser pad attachment for typewriters, by means of which the pressure is taken off of the carbon sheets while making an erasure, so as to avoid the ill-appearing 20 "smudge" usually seen on the carbon sheets.

Another object of the invention is to provide an eraser pad attachment for typewriters, which may be made to assume a normally inoperative position, but can be 25 moved around into place when there is use therefor.

Other objects and advantages will appear in the following specification, reference being had to the accompanying drawing in 30 which:

Figure 1 is a plan view of so much of a typewriter as necessary to illustrate the invention,

Fig. 2 is a perspective view of the eraser 35 pad detached from the machine,

Fig. 3 is an elevation viewed from the left end, and

Fig. 4 is a detail perspective view of the right support or keeper.

40 The invention consists of a bar 1 pivoted at 2 to the ear 3 of the fixed support 4 at the left. The support 4 is affixed to the typewriter 5 in any suitable way.

A right support or bar keeper 6 has a receiver notch 7 into which the free end of the bar 1 is fitted when it is desired to make an erasure. Under some circumstances, the bar 1 may be retained in the receiver notch, and in others, the bar may be swung back out of 50 the way. The positioning of the eraser bar is, however, a matter of small concern and the bar may be disposed of to suit the desires of the operator.

A covering 8 of paper or any other soft material is applied to the bar 1, substantially as shown in the drawing. Here it may be observed that the bar 1 can be made of metal, wood, rubber or any other composition, and similarly, it may be covered with rubber, paper or it may be left uncovered. 55 60

There is also considerable room for variation in the manner of mounting the device, because it is anticipated that in order to apply it to the various makes of machines now on the market, the shape of the supports 4 and 6 will have to be altered to suit. In the present instance, the invention is shown applied to an "Underwood" typewriter, wherein the disposition of the parts is such that the bar 1 can be swung straight 70 back.

A fingerpiece 9 at the right end forms a convenient place to grasp the bar. This fingerpiece is formed by simply twisting the bar through a half turn. Should it be desired to mount the eraser pad so that it may be moved in a direction other than horizontally as shown, obviously such a modification may readily be made. 75

In operation the sheet requiring erasure is 80 turned up far enough so that the place containing the incorrect word may lie directly on the eraser pad. Only the sheet requiring the erasure comes on top of the pad. The pad being supported at both ends, provides 85 a firm erasing base.

The carbon sheets are treated in the same manner, all sheets, excepting the one requiring erasure, being either slipped under the eraser pad or carried forwardly, thus revealing only the part requiring erasure. It is optional with the operator whether the eraser pad shall always assume the position shown in Fig. 1 or it shall be folded back. It will be easier to manipulate the typewriter by letting the bar remain in the operative position in Fig. 1. 90 95

While the construction and arrangement of the eraser pad as herein described and claimed, is that of a generally preferred 100 form, obviously modifications and changes may be made without departing from the spirit of the invention or the scope of the claim.

I claim:

An eraser pad attachment for typewriters, 105

comprising a bracket support with an ear for one end, arranged to be affixed to one end of a typewriter carriage; a single flat bar pivotally mounted at one end to said ear and including a suitable fingerpiece at the free end, a suitable pad covering the major

portion of the bar, and a bracket support for said free end of the bar arranged to be affixed to the other end of the carriage, and including a receiver notch to receive the bar 10 when turned thereinto in a horizontal plane.

JAMES H. POU, JR.
